REPEAT LOADING MECHANISM FOR
PNEUMATIC GUNSWilliam S. Wells, Palo Alto, Calif., assignor to
Daisy Manufacturing Company, Plymouth,
Mich., a corporation of Michigan

Application July 21, 1947, Serial No. 762,394

1 Claim. (Cl. 124—51)

1

This invention relates generally to guns and refers more particularly to guns adapted to fire shot either of the ball or pellet type.

One of the objects of this invention is to provide a gun of the above type with an improved auto-loading mechanism characterized in that it is simple in construction and reliable in operation. In accordance with this invention a magazine adapted to contain a multiplicity of shot is supported on the gun frame with the delivery end positioned adjacent the breech end of the barrel and provision is made for automatically transferring shot from the delivery end of the magazine to a position in registration with the breech end of the gun barrel.

Another object of this invention is to provide means for transferring shot from the delivery end of the magazine into the gun barrel in advance of the firing pin in response to manipulation of the cocking mechanism to lock the gun.

Still another feature of this invention is to provide the gun with short transferring means of the above type having provision for holding shot in a position at the breech end of the gun barrel for engagement by the positioning pin as the latter is operated by return movement of the cocking mechanism to advance the shot to its firing position in the gun barrel.

A further object of this invention is to provide means operating in timed relation to engagement of the shot by the positioning pin to return the shot transfer means to a position in operative relation to the delivery end of the magazine.

The foregoing as well as other objects will be made more apparent as this description proceeds, especially when considered in connection with the accompanying drawing, wherein:

Figure 1 is a perspective view partly in section of a part of a gun embodying auto-loading mechanism forming the subject matter of this invention;

Figure 2 is a sectional view taken on the line 2—2 of Figure 1;

Figure 3 is a sectional view showing the parts in a position wherein the positioning pin is in its advanced position in the gun barrel;

Figure 4 is a sectional view taken on the line 4—4 of Figure 2 and showing the positioning pin on its initial retracting stroke;

Figure 5 is a sectional view similar to Figure 4 showing the parts in a position wherein the firing pin is in its fully retracted position;

Figures 6 and 7 are sectional views taken respectively on the lines 6—6 and 7—7 of Figure 2;

Figure 8 is a fragmentary perspective view showing the pellet supply tube;

2

Figure 9 is an elevational view partly in section of the construction shown in Figure 8; and

Figure 10 is a sectional view taken on the line 10—10 of Figure 9.

For the purpose of illustrating the auto-loading mechanism forming the subject matter of this invention, I have selected a pneumatic gun of the general type shown in my copending application Serial No. 762,391, filed July 21, 1947 and now abandoned. However, it will be understood as this description proceeds that the auto-loading mechanism is not necessarily limited to use in connection with guns of the specific type noted above, but may be advantageously used in practically all instances where it is desired to provide repeat operation in guns designed to fire shot either of the pellet or ball type.

With the above in view, reference is now made to the accompanying drawing, wherein the reference numeral 10 indicates the breech end of a pneumatic gun having a frame 11 comprising a barrel 12, a storage chamber 13 for air under pressure and cocking mechanism 14 suitably supported on the frame 11 at the breech end of the barrel 12. The rear end of the chamber 13 is provided with an outlet opening 15 communicating with the barrel 12 at a point spaced forwardly from the breech end of the latter through a passage 16. The flow of air under pressure from the chamber 13 to the barrel 12 through the passage 16 is controlled by a valve 17 comprising an annular flat seat 18 surrounding the opening 15 and a valve member 19 preferably formed of rubber, synthetic rubber or a material having similar characteristics. The valve member 19 is supported by a tube 20 for sliding movement and is normally urged into engagement with the seat 18 by the fluid under pressure in the storage chamber 13. The specific construction of this valve and the manner in which the same operates is described at some length in the above identified copending application.

The valve 17 is momentarily opened against the action of the air under pressure in the chamber 13 by a plunger 21 and an anvil 22. The plunger 21 is slidably supported in the frame 11 of the gun with the opposite ends respectively engaging the valve member 19 and anvil 22. The anvil 22 is slidably supported in a compartment 23 in axial alignment with the plunger 21 and is engageable with the rear end of the latter. As shown in Figure 2 of the drawing the anvil 22 is secured to the front end of a rod 24 having the rear end slidably supported in a breech block 25. The rod 24 forms a support for a hammer 26 normally urged in a direction toward the anvil

22 by a coil spring 27 surrounding the rod 24 in the rear of the hammer. The rear end of the spring 27 abuts the breech block 25 and the front end of the spring engages a head 28 formed on the rear end of the hammer.

The hammer 26 is held in its cocked position shown in Figure 2 of the drawing wherein the spring 27 is compressed by a sear 29 actuated in accordance with the usual practice by a trigger operated trip 30. The arrangement is such that operation of the trigger (not shown) to release the sear 29 from the head 28 on the hammer 26 permits the spring 27 to throw the hammer forwardly along the rod 24 into engagement with the anvil 22. Inasmuch as the anvil engages the rear end of the plunger 21 and since the front end of the latter engages the valve member 19, it follows that the impact applied to the anvil by the hammer is transmitted to the valve member 19. The strength of the spring 27 is predetermined to apply sufficient force on the valve member 19 to overcome the opposing force applied to the valve member by the pressure of the air in the storage chamber 13 and effect movement of the valve member in a direction away from its seat 18. Thus, air under pressure from the chamber 13 escapes into the barrel 12 through the passage 16.

It will, of course, be understood that prior to opening the valve 17, a shot such for example, as a pellet 31 is located in what may be termed a firing position in the barrel in advance of the passage 16 so that the air under pressure admitted to the barrel impinges on the pellet and propels the latter through the barrel. The shot 31 is advanced along the barrel to its firing position by a pin 32 slidably supported on the gun frame for movement into and out of the breech end of the barrel.

The shot positioning pin 32 forms a part of the cocking mechanism 14 which also comprises a block 33 and a sleeve or cap 34. The block 33 is suitably supported on the frame 11 beyond the breech end of the barrel 12 for sliding movement in directions toward and away from the breech end of the barrel and is connected to the rear end of the positioning pin 32. The cap 34 extends over the breech end of the gun frame, and is supported at opposite sides of the gun frame by ways 35 for sliding movement fore and aft of the frame. The cap 34 affords a convenient grip and is connected to the block 33 for operating the latter.

Referring again to Figure 2 of the drawing, it will be noted that a lug 36 in the form of a screw is secured to the block 33 and projects into the path of travel of the head 28 on the hammer 26. The arrangement is such that rearward movement of the block 33 by the cap 34 subsequent to firing the gun engages the projection 36 with the front side of the head 28 on the hammer 26 and moves the hammer rearwardly along the rod 24. As the hammer is retracted the spring 27 is compressed and when the head 28 assumes a position rearwardly of the sear 29, the latter is moved to a position at the front side of the head to hold the hammer in its retracted position. The shot positioning pin 32 is retracted with the block 33 and the front end of the pin assumes a position rearwardly beyond the shot loading slot 37 at the breech end of the barrel 12 when in its retracted position relative to the barrel.

Supported at one side of the barrel 12 is a magazine 38 adapted to hold a multiplicity of shot in side by side relationship axially of the

magazine. The magazine comprises a tube 39 and a bore 40 formed in the gun frame 11 in juxtaposition to the breech end of the barrel 12. The axis of the bore 40 is parallel to the barrel 12, and the rear end of the bore communicates with the slot 37 at the front side thereof in the manner clearly shown in Figures 4 and 5 of the drawing. The front end of the bore is enlarged to receive the rear end of the tube 39 and the latter is removably attached to the barrel by a clip 39' to enable readily interchanging the tube 39, when empty, with a similar tube filled with shot. The clip is secured to the front end portion of the tube 39 and has a portion 40' shaped to enable snapping the same over the adjacent portion of the gun barrel in the manner clearly shown in Figure 10 of the drawing. The bore in the tube forms a continuation of the bore 40 in the frame 11 and shot is transferred from the tube 39 to the bore 40 by the action of gravity when the muzzle end of the gun is tipped upwardly.

Positioned beyond the rear or delivery end of the bore 40 is an abutment 41 comprising vertically spaced ears 42 projecting laterally from the gun frame 11. The front edges of the ears 42 are spaced rearwardly from the delivery end of the bore 40 a distance slightly greater than the length of the shot 31 and prevent delivery of more than one shot at a time from the bore 40. As the shot 31 falls by gravity from the delivery end of the bore 40 into the slot 37, it is restrained from displacement in a lateral outward direction by a retainer 43 in the form of a U-shaped clip fixed to the front end of a lever 44 having the rear end fulcrumed on the breech block 25 in the manner indicated by the numeral 45 in Figures 3 to 5 inclusive of the drawing. The front end of the lever projects between the ears 42 on the abutment 41, and the fulcrum is such as to enable swinging movement of the front end portion of the lever in directions toward and away from the barrel 12.

The front end of the lever 44 is urged in a direction toward the barrel 12 by a spring 47 positioned at the side of the breech block 25 opposite the side of the latter on which the lever is fulcrumed and assembled on a pin 48 extending transversely through a bore formed in the block 25. The end of the pin 48 adjacent the lever 44 extends through an opening formed in the lever at a point spaced forwardly of the fulcrum 45 and is formed with a head 49. A washer 50 is secured to the opposite end of the pin 48 and the spring 47 is located between the washer and adjacent face of the block 25. As the spring 47 swings the front end of the lever inwardly or in a direction toward the barrel 12, a shot 31 is transferred by the retainer 43 from a position in the slot 37 at the delivery end of the bore 40 (Figure 3 of the drawing) to a position in registration with the breech end of the barrel 12 (Figure 5 of the drawing) in advance of the positioning pin 32.

The lever 44 is normally held against the action of the spring 47 in the position shown in Figure 3 of the drawing wherein the retainer 43 serves as a closure for the outer end of the slot 37 to prevent displacement of the shot 31. For holding the lever 44 in the above position, a stop 51 in the form of a screw is threaded in a transverse bore formed in the cocking block 33 and having one end positioned to abut the inner face of the lever intermediate the retainer 43 and pin 48. A cam 52 projects inwardly from the inner face of

the lever 44 in a position to engage the outer end of the screw 51 and hold the swinging end of the lever in its outermost position when the positioning pin 32 is in its advanced position in the gun barrel. The stop or screw 51 is adjustable to enable accurately locating the retainer 43 at the swinging end of the lever 44 in a position to permit unobstructed movement of shot 31 into the slot 37 when the muzzle end of the barrel is tipped upwardly.

The extent of movement of the rearwardmost shot or pellet 31 into the slot 37 is actually limited by a fin 53 projecting laterally outwardly from the positioning pin 32 into the slot between the ears 42 on the abutment 41. The design of the fin is such that when the action is closed and the positioning pin 32 is in its advanced position shown in Figure 3 of the drawing, the front end of the fin acts as a stop for the rearwardmost pellet dropping out of the bore 40 into the slot 37. Actually, in the above position of the parts, the front end of the fin 52 is spaced from the rear end of the bore 40 a distance less than the length of the shot or pellet 31 so that the extreme front end of the pellet remains in the bore until the pin 32 is retracted. As the positioning pin is retracted from the gun barrel, the fin 52 is withdrawn from the slot 37 and the adjacent shot or pellet is loosened. At the same time, the screw 51 is released from the cam 52 and the lever 44 is operated by the spring 47 to move the pellet to its loading position. Thus, any tendency for adjacent pellets to cup is reduced to a minimum and jamming of the shot is avoided.

After the gun is fired it is, of course, necessary to cock the gun, and as stated above, this is accomplished by grasping the sleeve or cap 34 and moving the same rearwardly from the position thereof shown in Figures 1 and 2 of the drawing. Rearward movement of the cap 34 imparts a corresponding movement to the block 33 and enables the latter to compress the operating spring 21 by moving the hammer 26 rearwardly to its cocked position. Inasmuch as the positioning pin 32 is connected at its rear end to the block 23, it follows that this pin is retracted from the barrel and eventually assumes the position shown in Figure 5 of the drawing wherein the front end thereof is spaced rearwardly from the slot receiving slot 37.

The adjustable stop 51 moves rearwardly with the block 33 and as this stop approaches the pin 48, the front end of the lever 44 is swung inwardly by the spring 47 to transfer shot 31 into the breech end of the barrel in advance of the front end of the positioning pin 32. The positioning pin 32 is, of course, advanced into the barrel 12 when the cap 34 and associated cocking block 33 are returned to their forwardmost positions shown in Figures 1 to 3 inclusive of the

drawings. As the positioning pin 32 is advanced into the barrel 12, the shot 31 is engaged by the front end of the pin and is moved to its firing position in advance of the air passage 16.

What I claim as my invention is:

A gun comprising a frame having a barrel, a magazine for holding shot supported to one side of the barrel with the delivery end positioned adjacent the breech end of the barrel, means on the gun frame spaced rearwardly from the delivery end of the magazine providing a pocket adjacent the frame end of the barrel for successively receiving shot from the magazine, a lever having the front end positioned at the outer side of the pocket laterally beyond the delivery end of the magazine, means pivotally supporting the rear end of the lever on the gun frame and permitting movement of the front end of the lever laterally inwardly to transfer a shot in the pocket into the breech end of the barrel, resilient means urging the lever in a direction to transfer shot from the pocket to the breech end of the barrel, a shot positioning pin movable into and out of the barrel, a fin connected with the shot positioning pin and projecting laterally therefrom into said pocket adjacent the delivery end of said magazine when the shot positioning pin is in its advanced position so as to prevent said rearmost shot from moving into the pocket even if the gun frame is tilted, positioning means connected with the shot positioning pin and engageable with the lever in the advanced position of the shot positioning pin to hold the swinging end of the lever at the outer side of the pocket against the action of said resilient means, and a cam surface on said lever coacting with said positioning means upon retracting movement of said shot positioning pin to permit laterally inward swinging movement of the lever for transferring a shot from the pocket to the breech end of the barrel after said shot positioning pin and its shot engaging means have been retracted.
